UNITED STATES PATENT OFFICE.

DAVID D. BUICK, OF DETROIT, MICHIGAN.

DESIGN FOR A TANK.

SPECIFICATION forming part of Design No. 32,593, dated April 24, 1900.

Application filed March 31, 1900. Serial No. 11,021. Term of patent 14 years.

To all whom it may concern:

Be it known that I, DAVID D. BUICK, a citizen of the United States, residing at Detroit, in the county of Wayne and State of Michigan, have invented and produced a certain new and original Design for a Tank, of which the following is a specification, reference being had therein to the accompanying drawings, in which—

10 Figure 1 is a perspective view, and Fig. 2 is a vertical cross-section.

The body of the tank is substantially rectangular in plan and comprises an upper portion A and a lower portion B, the latter swelling out in front. The rear wall C and end walls D are perpendicular, while the front wall comprises upper and lower portions a and b, parallel to the rear wall in different vertical planes and connected by an inclined 15 and rounded portion c. At the top of the portion a is an inclined and rounded portion d, connecting with a flat top E. The end walls project slightly beyond the top and front walls and are grooved or beaded on their projecting edges, as shown at e. They are also 25 provided with a centrally-raised panel forming a surrounding border portion g, parallel with the edges of the wall.

The leading feature of the design is the body rectangular in plan, having the lower 30 portion swelling out in front, the vertical rear and end walls, and the front wall, having the upper and lower vertical portions a and b and the rounded inclined portions c and d.

What I claim as my invention is—35 The design for a tank, substantially as herein shown and described.

In testimony whereof I affix my signature in presence of two witnesses.

DAVID D. BUICK.
